MUFFLING MECHANISM FOR COMPRESSOR VALVES

Lars Hanson, Syracuse, N. Y., assignor to Carrier Corporation, Syracuse, N. Y., a corporation of Delaware

Application June 10, 1946, Serial No. 675,610

4 Claims. (Cl. 137—69)

1

This invention relates to valve structures and more particularly to valves employed in fluid compressors such as the reciprocating compressor of a refrigeration system.

Heretofore considerable difficulty has been encountered with compressor valves of the annular ring type because of their tendency to be noisy in operation. While relatively quiet operation may be obtained by using thin flexible valves, such valves are not durable or reliable and need be replaced frequently. While a smaller valve area creates less noise, a large valve area is necessary for high efficiency. From the standpoint of performance and reliability it has been preferred to use relatively rigid and heavy valves of large area even though they are noisier in operation.

The chief object of the present invention is to provide improved valve mechanism including noise muffling or dampening means.

An object of the present invention is to provide an improved muffler for valve mechanism of fluid compressors.

A further object is to provide an inexpensive valve which is relatively simple and inexpensive to manufacture and which is quiet and reliable in operation.

This invention relates to valve mechanism including in combination a cover member or valve plate, a valve guide member mounted adjacent the cover member, port means in the cover member, a valve adapted to control gas flow through the port means, yieldable means for urging the valve toward said port means, means for muffling the noise created by movement of the valve, said muffling means forming a passage for gas discharged through the port means, and means in the guide member permitting the passage of gas into the muffling means, the muffling means having an opening therein for the discharge of gas.

The attached drawing illustrates a preferred embodiment of my invention in which:

Figure 1 is a fragmentary sectional view through a reciprocating compressor embodying the present invention; and

Figure 2 is a sectional view taken on the line 2—2 of Figure 1.

Referring to the drawing there is illustrated a compression cylinder 2 in which a piston 3 operates. A valve plate or cover member 4 is shown mounted over cylinder 2. A port 5 is disposed in plate 4 for the discharge of gaseous refrigerant from the cylinder into the cylinder head 6. A valve 7 is disposed in position to close port 5. A valve guide member 8 is secured to plate 4 by suitable fastening means 9. Valve

2

guide 8 is provided with a recess for the reception of a plurality of springs 10 adapted to urge valve 7 toward port 5. A chamber 11 is formed in the valve guide 8 and is adapted to receive gas from port 5. A plurality of openings 12 and 13 extend through valve guide 8 and connect chamber 11 with the space enclosed by the cylinder head 6.

It will be understood that suitable intake and suction valves are provided to admit gaseous refrigerant into the portion of the cylinder 2 where it is compressed by piston 3 and then discharged through port 5. Such means per se are well known in the art and do not require a detailed description.

15 A muffling member designated generally at 14 is disposed about valve guide 8 and serves to muffle or dampen the sound created by movement of valve 7 and the fluid. Muffling member 14 comprises a vertically extending element 15 seated on plate 4 and spaced from the exterior wall of valve guide 8 to form a passage 16 for gas. A flange 17 extends horizontally from element 15 and inwardly over valve guide 8. The terminal portion 18 of flange 17 extends downwardly and seats on guide 8. An opening 19 is provided in terminal portion 18 for the passage of gas into the cylinder head. Gas discharged through port 5 passes through chamber 11 and passage 12 into passage 16 formed between element 15 and the exterior wall of guide member 8. Fastening means 20 secures element 15 to plate 4.

20 A second element 21 is provided in the form, for example, of a cup-like cylindrical washer secured by fastening means 9 to the guide member 8 and plate 4. Element 21 extends horizontally as shown at 22 in the plane of flange 17 to form a passage 23 for gas between horizontal portion 22 and the exterior wall of valve guide 8. Gas from port 5 enters chamber 11 and passes through passage 13 into passage 23. Elements 15 and 21 preferably are spaced apart to provide an opening 24 for the discharge of gas into the space enclosed by cylinder head 6. Opening 19 in the terminal portion 18 of flange 17 opens into passage 23 immediately below opening 24 so that the gases from passages 16 and 23 are free to pass into the space enclosed by cylinder head 6. It will be understood elements 15 and 21 may be integral with one another if desired, suitable provision being made for the discharge of gas therefrom into the space enclosed by cylinder head 6.

25 In the operation of the device, gas is compressed in cylinder 2 by means of piston 3. The compressed gas is discharged through port 5 and the amount of gas discharged is controlled by valve 7. Gas passing through port 5 enters chamber

11. From chamber 11 the gas passes through a plurality of openings 12 and 13 in valve guide 8 and into passages 16 and 23. Passages 16 and 23 are designed to obtain a difference in length of the gas passages equal to one-half of the wave length corresponding to the frequency of the noise created by the movement of valve 7. It will be understood that by proper dimensioning of the distances between the elements of the muffling member 14 and the valve guide member 8, a substantial reduction in noise may also be obtained by the effect of the reflected wave.

My invention provides a simple and inexpensive valve mechanism which is quiet and reliable in operation. The muffling member provided by my invention serves to reduce considerably the noise created by movement of a valve governing the directional flow of gas and thus renders the valve extremely quiet in operation.

While I have described and illustrated a preferred embodiment of my invention, it will be understood my invention is not limited thereto since it may be otherwise embodied within the scope of the following claims.

I claim:

1. In mechanism for muffling sounds in compressor valve structures, the combination of a cover member, a valve guide member mounted adjacent said cover member, port means in said cover member, a valve adapted to control gas flow through said port means, yieldable means disposed in said guide member for urging said valve toward said port means, a chamber formed between the cover member and the guide member for the discharge of gas from said port means, a muffling member disposed about said guide member, said member including a first element adapted to form a passage for gas, and a second element adapted to form a second passage for gas, and a plurality of passages connecting the passages in said muffling member with said chamber, said first element being spaced from said second element to form an opening for the discharge of gas from the muffling passages.

2. In mechanism for muffling noises in compressor valve structures, the combination of a cover member, a valve guide member having vertical and horizontal walls mounted adjacent said cover member, port means in said cover member, a valve adapted to control gas flow through said port means, yieldable means disposed in said guide member for urging said valve toward said port means, a chamber formed between the cover member and the guide member for the discharge of gas from said port means, a muffling member disposed about said guide member at a predetermined distance therefrom to form a passage therebetween adapted to muffle the noise created by movement of said valve, and a plurality of passages in said guide member connecting said chamber and the muffling member for the discharge of gas into said muffling passage, said muffling member including a vertically extending element seated on said cover member and spaced from the vertical wall of said guide member, a flange on said element extending inwardly and spaced from the horizontal wall of said guide member, the flange terminating in a downwardly extending portion seated on the horizontal wall of said guide member, the downwardly extending portion of said flange having an opening therein for the discharge of gas.

3. In mechanism for muffling noises in compressor valve structures, the combination of a cover member, a valve guide member having vertical and horizontal walls mounted adjacent said cover member, port means in said cover member, a valve adapted to control gas flow through said port means, yieldable means disposed in said guide member for urging said valve toward said port means, a chamber formed between the cover member and the guide member for the discharge of gas from said port means, a muffling member disposed about said guide member at a predetermined distance therefrom to form a passage therebetween adapted to muffle the noise created by movement of said valve, and a plurality of passages in said guide member connecting said chamber and the muffling member for the discharge of gas into said muffling passage, said muffling member including a vertically extending first element seated on said cover member and spaced from the vertical wall of said guide member to form a passage therebetween, a flange extending inwardly therefrom and spaced from the horizontal wall of said guide member to form a continuation of the passage, said flange terminating in a downwardly extending portion seated on the horizontal wall of said guide member, the downwardly extending portion of said flange having an opening therein for the discharge of gas from the passage, means securing the first element to the cover member, and a second element adapted to cooperate with said first element, said second element including a horizontally extending flange spaced from said guide member and adapted to form a passage therebetween, said first element being spaced from said second element to form an opening for the discharge of gas from the muffling passages, and means securing said second element in position on said guide member.

4. In mechanism for muffling noises in compressor valve structures, the combination of a cover member, a valve guide member mounted adjacent said cover member, port means in said cover member, a valve adapted to control gas flow through said port means, yieldable means for urging said valve toward said port means, a chamber formed between the cover member and the guide member for the discharge of gas from said port means, a muffling member disposed about said guide member including a first element spaced from the wall of said guide member to form a passage therebetween, a second element having at least a portion thereof spaced from said guide member to form a passage therebetween, said first element being spaced from said second element to form an opening for the discharge of gas from the passages, and a plurality of passages in said guide member connecting said chamber and the passages in said muffling member for the discharge of gas into said muffling passages.
